BOOK COVER AND INDEX

John Schade, Holyoke, Mass., assignor to National
Blank Book Company, Holyoke, Mass., a cor-
poration of Massachusetts

Application May 1, 1933, Serial No. 668,697

7 Claims. (Cl. 116—119)

This invention relates to an improved combination of a book, separable index sheets for the book, and a book cover to not only protect the book and index sheets but also to bind the combination together in a new and useful manner.

According to one feature of the combination the invention is planned to simplify the construction of the parts and to make them in a form for more conveniently changing the book part of the combination than in prior art structures.

Other features will be apparent from the drawing, detailed description, and annexed claims.

In the drawing,

15 Fig. 1 shows a perspective view of the index sheets slightly spaced apart, with two of them shown in full lines, and dotted lines indicating others that can be inserted in a bound book;

20 Fig. 2 shows a perspective view of a book such as a large telephone directory with two index sheets in place and dotted lines indicating other pages and index sheets ready to be inserted in its cover;

25 Fig. 3 shows a perspective view of the covered book combination as it appears in use, with parts dotted;

30 Fig. 4 shows a perspective view of the metallic binder construction carried by the cover on the inside of its back portion, and with one index sheet shown in dotted position indicating the way in which such sheets are held by the binder;

35 Fig. 5 shows a detail view of the binder construction at one end; and

Fig. 6 shows a detail of a modified construction.

40 In carrying out my invention I make up a set of individual index sheets 1. Each sheet is preferably made the same size as the bound sheets in the book to be indexed except in width. The width is long enough for an outer margin to extend beyond the sheets of the book when the loose index sheet is tucked in between the bound sheets as far as it will go. At the upper and lower corners of each index sheet I provide rectangular tab extensions 2 and 3. I place those tabs so that 45 they are very close to the inner line of the sheet and with enough area in the short tabs to prevent easy bending or twisting. Such tabs may be an integral part of the index sheet, especially when such sheets are made of heavy enough stock to 50 serve the tabs in giving strength. But I prefer and consider it an optional feature of my invention to make the index sheets thin enough to be tucked way down between sheets of the bound book so as to be retained in place to a large extent by the normal pressure between such bound

5 sheets close to the line of binding. In this way the loose index sheets will be held in place without depending so much on the tabs as binding parts for the loose sheets, all as will appear. In the construction shown I have indicated the tabs 2 and 3 as made thicker than the index sheets. Such tabs may be conveniently made of celluloid. Their upper edges are preferably just a small distance from the line of their inner edges so that both are near the hinge line of the bound leaves. 10

15 The index leaves are inserted in a telephone directory, for example, as indicated in Fig. 2. In such use the sheets are far enough apart in the book that their extensions at the sides do not need to be in staggered arrangement but that construction for the side extension may be used. With the bound book thus indexed it is applied to the cover shown in Fig. 4. The tabs 2 extending from the upper edge of the book are hooked under one of the curved shelves 4 of the metallic binder 20 or loose leaf structure. One of these shelves 4 shown at the upper edge is preferably stationary and not mounted for movement. The other one 5 at the lower end is hinged at 6 so as to turn up and allow the lower set of tabs to be put in position with the back of the book parallel and against the back of the cover. Then shelf 5 is turned to overlie the tabs at the bottom edge of the book as shelf 4 overlies the tabs at the top. 25

30 To retain shelf 5 in tab holding position its end opposite the hinge is provided with a cylindrical opening 7 to receive a headed pin 8, the inner end of which enters an aligned tubular opening 9 provided in the stationary part of the metallic binder part 10. A spring 11 is adapted 35 to act as a keeper by engaging the shoulders 12 of pin 8 when the latter is pushed home.

Thus, the insertion of the indexed book in the cover is an extremely simple operation. The tabs are hidden by the end plates or outer skirts 13 shown for shelves 4 and 5 which makes a good 40 appearance at the end of the book. The removal of the bound book from its indexing cover parts is also extremely simple. Pin 8 is released by "thumbing" up spring 11, pulled out to release 45 shelf 5, the latter is turned on its hinge and the bound book with its index leaves is lifted out.

50 The index leaves can be inserted in a new edition of the telephone directory or other book and the new edition placed in combination with the cover all with very little trouble. It is desired not only to avoid trouble in the operation, but to make it so easy to do that the user will not feel the same burden of manipulation that prior 55 art structures have required.

In the use of the combination the index leaves are carried along with the bound leaves and with no chance for the tabs to bind. The tabs under the shelves 4 and 5 are not placed there for a hinging action. When the combination is laid down on a table for use as a book the tabs fall away from shelves 4 and 5, being carried downwardly by the book. The shelves are located to permit such play of the parts. When the leaves are turned the tabs are turned with them and slide with relation to the shelves 4 and 5 and for the most part out of contact therewith. It is only when the combination is held with the bound book hanging downwardly that the tabs come into full play against the shelves 4 and 5 to retain the bound book in the cover. There are enough tabs to do this without much strain on any one. Thus, the tabs will accomplish their retaining function without being necessarily of metal or bulky construction, but simple unperforated tabs at the inner ends of the index leaves. The latter being thin, and pinched in between the bound leaves of the book, tend to move always with the book. To a substantial extent the strain on the tabs is eliminated by permitting a very loose play for them under shelves 4 and 5 and depending upon their acting against the shelves as a group to retain the parts together, which is needed for the most part when the book is closed.

I have shown in Fig. 6 a detail modification of the tab and shelf engaging parts made in a form to stand extra strain. In this modification tabs 2' may be made like those of the other figures except that where they contact with shelf 4' (at one end and likewise at the other end in contact with the corresponding shelf not shown in Fig. 6) the edge is rounded or hook-shaped as at 15. The shelf 4' (and the corresponding one at the other end) is provided with a beaded edge 16 to mate with the rounded edge of tab 2'. This is desirable in some cases where the particular use would otherwise require a stronger tab. The rounded surface engagement of tab and shelf indicated in Fig. 6 is a little more expensive to make, but has advantages as a detail combined with my broader invention.

When desired, my invention contemplates making one or more of the index sheets (preferably one near the center of the pack) reinforced by a band at the inside edge, such as might be made of metal to include the edge and both tabs. Such an index sheet would hold the combination together against enough strain to tear the weaker tabs on the other index sheets. Then the tabs on the latter would serve primarily to prevent the index sheets from falling out. Of course much the same result would be secured if a wire rod or flat steel spring were used instead of the reinforced index sheet, to bind the book in the cover, and all the index sheets could then be of the same character. In the latter case the tabs would be holding the index sheets in the combination but without the strain due to holding the bound book in the combination. All these arrangements are contemplated in the broader features of the invention as claimed.

What I claim is:

1. In combination a book cover having loose leaf structure on the inside face of its back portion, inwardly extending end flanges on said structure spaced from the back portion, a set of index sheets fitting the cover between said end flanges, said index sheets having outwardly extending tabs to underlie said end flanges, one of

said flanges being movably mounted so as to permit the placing in and removal of the index sheet tabs from underlying position with respect to both flanges without the bending of said index sheets or tabs, said index sheets being arranged for insertion at spaced intervals in a bound book and to hold the latter in the cover. 5

2. In combination a book cover, a loose leaf structure fastened inside the back portion of the cover, end flanges on said loose leaf structure extending transversely of the back portion, a set of index sheets for temporary binding in the cover, said sheets having tabs at their back corners for underlying said flanges, means forming part of the loose leaf structure for movably mounting one of said flanges to release the tabs and a latch to retain said flange against movement. 10 15

3. In a temporary binder of the type in which a loose leaf structure binds a set of index sheets which are inserted in a bound book whereby the latter is both temporarily covered and indexed by the binder, the combination of a set of index sheets provided with top and bottom tabs at the inside corners, a loose leaf structure on the binder provided with end pockets to receive and form the sole retaining means for said tabs, one of said pockets being movably mounted on the loose leaf structure, so as to provide for simultaneous end-wise insertion of the tabs in the opposite end pocket and simultaneous pocketing of the adjacent tabs by closing movement of one of the pockets. 20 25 30

4. In a temporary binder of the type in which a loose leaf structure binds a set of index sheets which are inserted in a bound book whereby the latter is both temporarily covered and indexed by the binder, the combination of a set of index sheets provided with top and bottom tabs at the inside corners, a loose leaf structure on the binder provided with end pockets to receive and form the sole retaining means for said tabs, one of said pockets being movably mounted on the loose leaf structure, so as to provide for simultaneous end-wise insertion of the tabs in the opposite end pocket and simultaneous pocketing of the adjacent tabs by closing movement of one of the pockets, and a latch to hold the movable pocket in tab retaining position. 35 40 45

5. In a temporary binder of the type in which a loose leaf structure binds a set of index sheets which are inserted in a bound book whereby the latter is both temporarily covered and indexed by the binder, the combination of a set of index sheets provided with top and bottom tabs at the inside corners, a loose leaf structure on the binder provided with end pockets to receive and form the sole retaining means for said tabs, one of said pockets being movably mounted on the loose leaf structure, so as to provide for simultaneous end-wise insertion of the tabs in the opposite end pocket and simultaneous pocketing of the adjacent tabs by closing movement of one of the pockets, said pockets having a sufficient capacity to provide for a very loose fit of the tabs so as to prevent wear and tear. 50 55 60 65

6. In a temporary binder of the type in which a loose leaf structure binds a set of index sheets which are inserted in a bound book, the combination of a set of index sheets for the bound book and a loose leaf structure provided with turned flanges at the ends of the binder back, hook-shaped tabs on said sheets to engage said flanges at their under sides, said flanges being provided with beaded ends to fit rounded hook portions of the tabs, said tabs and flanges forming the sole 70 75 75

binding connection between the sheets and binder.

7. In combination a temporary binder of the type in which a loose leaf structure binds a set of index sheets which are inserted in a bound book, a loose leaf structure fastened inside the binder back, inturned crescent-shaped flanges at the end of the binder to form open pockets, a bound book and a set of index sheets inserted in the book and provided with integral tabs extending outwardly above and below the bound sides

of the book, said tabs extending into said pockets to form with the latter the sole retaining means for the book in the binder, said pockets permitting a loose movement of the book between the planes where its back engages the back of the binder and the upper edges of the tabs engage said flanges, one of said flanges being mounted for movement by hand to and from binding and releasing position.

JOHN SCHADE. 10
